DETACHABLE BLADE BIT

Leslie A. Layne and Harold C. Block, Houston,
Tex.; said Block assignor to said Layne

Application February 4, 1933, Serial No. 655,198

4 Claims. (Cl. 255—61)

Our invention relates to well drills, and more particularly to the type of scraping bits known generally as fish tail bits.

It is an object of our invention to provide a fish tail bit wherein the blade portion thereof is detachable and to provide means in such a structure for easily and securely attaching the blade to the head.

It is a further object of the invention to provide means for securing the blade in position, which will allow for adjustment due to wear, so that the blade will constantly be held rigid even after wear has occurred.

Another object of the invention is to provide means for securing the blade frictionally in position, and, in addition thereto, to provide a holding means which will hold the blade positively against removal of the blade from the head.

The invention further resides in the general arrangement and construction of the blade and the head, an understanding of which will appear more clearly from the description which follows.

In the drawings herewith, Fig. 1 is a side view showing the blade in elevation and the head in central longitudinal section, a portion of the shank of the bit being broken away.

Fig. 2 is a side elevation of the blade detached from the head.

Fig. 3 is a top plan view of the blade shown in Fig. 2.

Fig. 4 is an edge view of the blade member shown in Fig. 2.

In constructing our improved bit we form a head 1 which may be cylindrical in outline but having a reduced upper end 2 for connection with the drill stem. Instead of the usual upwardly tapered shank we provide a downwardly tapered box 3 in the neck 2 of the bit to connect with a tool joint or drill collar, by means of which connection is made with the drill stem. At the lower end of the threaded socket 3 is a chamber 4, having a lower shoulder 5 therein, upon which the blade attaching means may contact.

The lower end of the head is formed with a transverse slot 6 therein to receive the blade 7. This slot is extended upwardly at each side, as shown at 8, to receive the upwardly extending wings 9 on the blade. The bit has an axial opening 10 therein extending from the chamber 4 through to the lower end. This opening is tapered upwardly so as to form a wedging fit with the shank 11 of the blade.

The blade 7 is of the usual fish tail form having its lower end divided at 12 midway of the width thereof and one edge of the blade is curved

in one direction and the other edge in the other, both sides of the blade being extended in a forward direction relative to the rotation of the bit. The shank 11 of the bit is tapered upwardly to fit the opening or socket 10 and is of sufficient length to project upwardly to a point spaced somewhat from the upper shoulder 5, as will be seen in Fig. 1.

The shank has an axial recess at its upper end, threaded at 13 to receive a locking bolt 14. It will be noted that when the shank 11 of the blade is in a wedging position within the opening or socket 10, the upper end 15 of each wing of the blade is spaced downwardly from the upper end of the opening 8 into which it fits. Likewise, the upper portion 16 of the blade, adjacent the lower end of the head is spaced from the head so that in case of wear of the shank in the socket the blade may be wedged further upwardly into position without coming to a stop against the upper portions of the slot in the head which receives the blade.

The locking bolt 14 may be screwed in place in the upper end of the shank by tools inserted downwardly through the upper socket 3 in the head. We contemplate the use of an annular plate or washer 17 having its lower end fitted within the opening 10 and adapted to receive the upper end of the bolt. We may provide a locking ring 18 between the head of the bolt and the plate or washer 17, so that when the bolt is tightened in the socket 13 it may serve to draw the shank more securely in position in the head and prevent any tendency of the bit to be lost in the hole.

The flushing fluid in this tool will pass from the chamber 4 through downwardly inclined water courses shown at 19 in dotted lines in Fig. 1. It is to be understood that there are two oppositely inclined water courses one on each side of the head, which tend to discharge the flushing fluid in front of the cutting edges of the blade.

The advantage of this construction lies in the fact that it is easily and quickly secured in position. The blade is inserted into the position shown in Fig. 1 and driven in place with a wedging fit of the shank in the socket 10. The wings 9 of the blade fit within the slot but have no action to secure the blade in position, the shank 11 being relied upon entirely to hold the blade in place. The locking bolt 14 is then inserted downwardly through the socket 3 and through the washer 17 and screwed within the threaded recess 13 in the shank. As the bolt is tightened

in position it will be seen that it will exert a further pull upon the blade, tending to move it into a rigid fit with the head from which it will not be removed in operation.

5. Due to the fact that the driving torque of the head relative to the blade is taken up by the sides of the slot 8, into which the blade fits, there will be no relative rotation of the blade relative to the head. Furthermore, due to the 10 fact that the weight of the head rests upon the blade there will be no heavy force tending to remove the blade from the head. The driving fit of the tapered shank 11 in the socket 10 will be entirely sufficient to hold the same against 15 removal. The locking bolt 14 is an extra provision which is made to prevent any accidental loosening of the shank in the socket. It is, therefore, simply a safety measure but ordinarily will not be necessary. It will be easily seen that 20 when the blade is to be removed the bolt may be unscrewed and withdrawn and a driving force exerted upon the upper end of the shank 11, forcing the blade from its position in the head so that it may be replaced by a newly sharpened 25 blade.

Having described our invention, what we claim as new is:

1. A fish tail well drill including a head having a diametrical slot at its lower end, an axial 30 upwardly-tapered socket in said head, a shoulder in said head at the upper end of said socket, a fishtail blade, a tapered shank thereon shaped to form a wedging fit in said socket when the upper end of said blade is spaced below the upper 35 end of said slot, a plate in said head engaging said shoulder, and a bolt extending through said plate and screwed within the upper end of said shank to secure said blade to said head.

2. A fish tail well drill including a head having 40 a diametrical slot at its lower end, upward extensions in said slot at its ends, an axial up-

wardly-tapered socket in said head, a shoulder in said head at the upper end of said socket, a fishtail blade, a tapered shank thereon shaped to form a wedging fit in said socket when the upper end of said blade is spaced below the 5 upper end of said slot, lateral, upwardly extending wings on said blade fitting within said extensions in said slot, adapted to take the driving torque from said head in the rotation of the drill, and means to fix said blade in rigid engagement 10 with said head.

3. A fish tail well drill including a head having a diametrical slot at its lower end, an axial upwardly-tapered socket in said head, a shoulder in said head at the upper end of said socket, 15 a fishtail blade, a tapered shank thereon shaped to form a wedging fit in said socket when the upper end of said blade is spaced below the upper end of said slot, channels for flushing fluid in said head extending from said shoulder downwardly on each side of said blade to discharge on the advancing sides of said blade above the cutting edges thereof, and means to fix said blade in rigid engagement with said head.

4. A fish tail bit for use with rotary drill stems 25 including a head, a blade fitting within a diametrical slot at the lower end of said head, an upper threaded socket in said head to receive the drill stem, an axial opening through said head communicating with said socket and forming a shoulder at the lower end of said socket, a central upwardly tapered shank on said blade having a frictional fit in the opening in said head, means to hold said blade in said head including a plate on said shoulder closing the 30 upper end of said opening, and a cap screw accessible through said socket and engaging through said plate to screw into said shank.
